Attorney.

UNITED STATES PATENT OFFICE.

HAROLD BLYE, OF GRAND RAPIDS, MICHIGAN.

HARDWARE CONSTRUCTION.

Application filed September 7, 1920. Serial No. 408,410.

To all whom it may concern.:

Be it known that I, HAROLD BLYE, a citizen of the United States of America, residing at Grand Rapids, in the county of Kent 5 and State of Michigan, have invented certain new and useful Improvements in Hardware Constructions; and I do hereby declare the following to be a full, clear, and exact description of the invention, such as will 10 enable others skilled in the art to which it appertains to make and use the same.

This invention relates to a hardware construction, being particularly concerned with a novel construction and method of making 15 the same which is applicable in many places in different hardware articles of manufacture. For instance, the present invention is concerned with the attachment of a cylindrical sleeve to a face plate such as is used 20 in locks and latches, one example of which is shown in Patent No. 1,327,695, issued Jan. 13, 1920, and another in my pending application Ser. No. 270,936, filed Jan. 13, 1919. In each, a cylindrical sleeve is attached to a 25 face plate which is adapted to set against a vertical edge of a door, the sleeve having the lock or latch housing connected therewith. My invention has for its primary object and 30 purpose, a novel and particularly effective means of attachment of the sleeve and plate, whereby an opening for the passage of the latch or lock bolt is made in the face plate, and an especially secure connection of the 35 sleeve and plate made which requires no cutting away or polishing away of projecting parts in order to make a smooth and finished article, and in which the connecting joint between the parts is of exceptional 40 strength. Various other objects and pur- 45 poses than those above enumerated will appear fully and in detail as understanding of the invention is had from the following description, taken in connection with the accompanying drawing, in which,

Fig. 1 is a perspective view of the connected sleeve and face plate, taken from the rear and to one side thereof.

Fig. 2 is a transverse section through the plate and sleeve.

Fig. 3 is a longitudinal section there- 50 through.

Fig. 4 is a rear elevation of the connected plate and sleeve, and

Fig. 5 is a perspective view of the plate 55 alone before attachment of the sleeve, the

view being taken from the rear and to one side of the same.

Like reference characters refer to like parts in the different figures of the drawing.

The face plate 1 is of the usual form, being rectangular in outline and relatively thin. Between its ends, at substantially its middle an annular flange 2 is made extending to the rear, there being an opening 4 made through the plate around which the flange 2 is located. Adjacent each end of the plate an opening 3 is made for the passage of screws or other equivalent securing devices for attaching the plate to a door at its free vertical edge.

The sleeve 5 has an inner diameter somewhat greater than the outer diameter of flange 2 and at one end is pressed or spun inwardly as indicated at 6, so that the opening at such end of the sleeve is but little larger than the outer diameter of flange 2. The sleeve is placed over the flange and a punch brought against the flange at opposite sides thereof, the effect of which is to divide the flange into four parts, two of which, indicated at 7 are crushed and bent outwardly against the inturned end 6 of the sleeve, while the other parts 4^a remain in position to serve as guides for the lock or latch bolt. The parts 7 are at opposite sides of the flange, and the parts 2^a between them are also at opposite sides as shown.

With the above described construction, a very secure connection of the sleeve and plate is made and one which leaves the outer side of the plate smooth and without projections to be smoothed and polished off as would be the case where ears extending from the sleeve pass through the plate for attachment of the sleeve to the plate. The construction is especially practical both from the manufacturing end and for utility. The appended claims define the invention, and I consider myself entitled to all forms of structure coming within the scope thereof.

I claim:

1. In combination a flat metal plate having an opening therein with a flange struck and projecting from the plate around the opening, and a sleeve formed at one end with an inturned portion which is located around the flange, parts of said flange being pressed against the inturned portion of the sleeve to permanently secure the sleeve to the plate, substantially as described.

2. In combination, a flat plate having an opening therethrough and a flange struck and projecting from the plate around the opening, and a sleeve formed at one end 5 with an inturned curved portion which is located around the flange, the flange being pressed against said inturned portion of the sleeve to permanently secure the sleeve to the plate, substantially as described.
- 10 3. In combination, a flat plate having an opening therein with a flange projecting from the plate around the opening, said

flange being divided vertically at a plurality of separated points, and a sleeve formed at one end with an inturned portion which is 15 located around the flange, separated parts of the flange being pressed against the inturned portion of the sleeve to permanently secure the sleeve to the plate, and the remaining parts of the flange extending into 20 the sleeve, substantially as and for the purposes described.

In testimony whereof I affix my signature.
HAROLD BLYE.
